UNITED STATES PATENT OFFICE.

AUGUST CARLEWITZ, OF NEWARK, NEW JERSEY.

DESIGN FOR A CORNICE.

SPECIFICATION forming part of Design No. 21,624, dated June 21, 1892.

Application filed May 5, 1892. Serial No. 431,962. Term of patent 7 years.

To all whom it may concern:

Be it known that I, AUGUST CARLEWITZ, a citizen of the United States, residing at the city of Newark, in the county of Essex and State of New Jersey, have invented and produced a new and original Design for a Cornice to be Made in the Angle Formed by the Wall and Ceiling of a Room, of which the following is a specification, reference being had to the accompanying drawings, showing a part thereof.

The drawings show one section of the entire cornice, the completed cornice being made up of such sections.

Figure 1 is a front elevation of the cornice, showing my design. Fig. 2 is a cross-section through the line *a a* of the same.

The prominent feature of my design consists in a raised figured surface, the outlines of which, when viewed in elevation, as in Fig. 1, will lie principally within the cove of the cornice, but also slightly extending over the upper and lower beads thereof.

In the drawings, A is the cove of the cornice, which is concave in form, and B C are respectively the upper and lower beads or moldings. The central feature of the design consists of the two large gracefully-disposed leaves D D, which are raised within the limits of the cove of the cornice. Branching from the stem of the leaves D is a flower E, also within the cove, and a tendril F, carrying seed-pods and buds, which extend over the upper and lower moldings.

What I claim is—

The design for a cornice, herein shown and described, the same comprising the upper and lower plain moldings B and C, the intervening plain cove A, in which is the figure of raised leaves and flowers, and seed-pods extending over the moldings B and C, substantially as set forth.

AUGUST CARLEWITZ.
